CLAIM

The ornamental design for an electronic musical instrument, as shown and described.

DESCRIPTION

FIG. 1 is a right side view of an electronic musical instrument showing our new design;

FIG. 2 is a bottom plan view of the electronic musical instrument of FIG. 1;

FIG. 3 is a rear elevational view of the electronic musical instrument of FIG. 1;

FIG. 4 is a front elevational view of the electronic musical instrument of FIG. 1;

FIG. 5 is a top plan view of the electronic musical instrument of FIG. 1;

FIG. 6 is a left side view of the electronic musical instrument of FIG. 1; and,

FIG. 7 is a top, rear, and left side perspective view of the electronic musical instrument of FIG. 1.

The broken lines showing a tube assembly extending from the left side of the instrument in the drawing views are included for the purpose of showing the environment of the electronic musical instrument and forms no part of the claimed design.

The broken lines shown on the left, top and bottom surface of the instrument in the drawing views are included for the purpose of showing the environment of the electronic musical instrument and forms no part of the claimed design.

1 Claim, 4 Drawing Sheets
